UNITED STATES PATENT OFFICE.

JESS C. HOVER, OF BINGHAMTON, NEW YORK.

FOLDING BOX.

SPECIFICATION forming part of Letters Patent No. 700,049, dated May 13, 1902.

Application filed July 11, 1901. Serial No. 67,873. (No model.)

To all whom it may concern:

Be it known that I, JESS C. HOVER, a citizen of the United States, residing at Binghamton, in the county of Broome and State 5 of New York, have invented a new and useful Folding Box, of which the following is a specification.

The present invention relates to folding or collapsible boxes, and in a more limited aspect to that class commonly known as "pyramidal" boxes, employed for holding ladies' hats and other articles which must be protected from dust and dirt or are liable to be crushed or injured if left exposed.

15 One of the objects of this invention is to greatly simplify the construction of folding boxes and yet provide a structure which may be folded compactly, can be readily set up, and when in the latter condition will have all 20 its joints covered, and thus completely exclude the dust from the interior thereof.

Another and very important feature resides in a structure that permits of gaining access to the interior through one of the sides. 25 In the boxes as ordinarily constructed the upper ends of the sides are tied together, and each time an article is placed therein the sides must be untied and the box practically collapsed and afterward set up again about 30 said article. By the present construction after the sides are secured together they may remain so and one side opened and closed without disturbing the set-up relation of the remaining portions.

35 The preferred embodiment of the invention is fully shown and described in the accompanying drawings and following specification. The construction set forth, however, is not to be limited to that shown and described, but 40 is open to such changes and modifications as are permitted by the scope of the claims appended hereto.

In the drawings, Figure 1 is a perspective view of the improved box. Fig. 2 is also a 45 perspective view, but showing one of the sides opened. Fig. 3 is a perspective view of the box when in folded or collapsed position. Fig. 4 is a plan view of the blank.

Similar numerals of reference designate 50 corresponding parts in all the figures of the drawings.

In the preferred embodiment of the invention the entire box is made of a blank formed from a single sheet of cardboard or analogous material. As shown in Fig. 4, this blank has 55 two parallel side edges and ends, each of which tapers to a central point and has a pair of tapering recesses extending inwardly from the same, said recesses being directly opposite each other and of the same depth. The 60 end sections thus formed are folded so as to be divided in three equilateral triangles of the same size, said folds being shown in dotted lines. The side portions between the recesses are folded on a line connecting the 65 apices of the recesses. The box thus formed comprises a rectangular bottom 10, to the opposite edges of which are hinged the tapering or triangular side walls 11. To the side edges of the wall 11 are hinged the side flaps 70 12, said flaps being triangular in form and of the same size as the wall. One flap of each wall is provided contiguous to its inner edge with a slit 13, while the other has a tongue 14 at its outer free corner formed by a slit 15, 75 that extends from the edge of the flap a suitable distance into the same. Hinged to the remaining side edges of the bottom are wings 16, said wings tapering toward their outer or free ends and being preferably trapezoidal 80 in form. Secured to the outer ends of the side walls 11 are suitable fastening devices in the form of ribbons or cords 17.

The manner of setting up the box will be 85 readily apparent. The wings 16 and the side walls are bent up, and said side walls are secured together at their upper ends by means of the fastening devices 17. The side flaps are then brought together over the wing 16 and will be located in overlapping relation. In 90 fact, in the present structure, because of their size, they will cover the open sides of the box. This will bring the tongues 14 and the slits 13 in coacting relation, so that said tongues may be inserted in the slits, and thus detachably 95 secure the overlapping side flaps together. When it is desired to obtain access to the box after having thus been set up, it is only necessary to remove one of the tongues from its slit, thereby releasing both side flaps 100 and permitting of their being thrown apart, as shown in Fig. 2. The wing 16, covered by

said flap, can then be thrown downwardly and an article inserted or removed through the open side.

It will be seen that an exceedingly simple construction is provided, in which there is a minimum amount of cardboard wasted in cutting the blanks. Furthermore, the structure when set up is very rigid and stable and the joints are completely covered, thereby making it practically dust and dirt proof. The boxing is also very convenient to operate when it is desired to place an article therein or remove it therefrom, as the entire structure does not have to be released or collapsed.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by means of Letters Patent, is—

1. In a pyramidal folding box, the combination with a bottom, of side walls hinged to the bottom and spaced from each other, said walls tapering toward their outer ends, side flaps hinged to the side edges of the walls and arranged to overlap when set up, and means carried by the flaps for detachably securing together the flaps which are on the corresponding edges of the side walls.

2. In a folding box, the combination with a bottom, of side walls hinged to the bottom and spaced from each other, said walls tapering toward their free ends, means for fastening the side walls together at their upper or free ends, side flaps hinged to the side edges of the walls, and interlocking means carried by the flaps for detachably securing together the flaps which are on the corresponding edges of the walls.

3. In a pyramidal folding box, the combination with a polygonal bottom, of side walls hinged to the opposite side edges of the bottom and tapering toward their free ends, means for securing the upper ends of the op-

posing side walls together, side flaps hinged to the side edges of the walls, said flaps being arranged in overlapping relation when the walls are set up, and means carried by the overlapping flaps for detachably securing them together.

4. In a pyramidal folding box, the combination with a polygonal bottom, of side walls hinged to the opposite side edges of the bottom, and tapering toward their free ends, side flaps hinged to the side edges of the walls, said flaps being arranged in overlapping relation when the walls are set up, one of the side flaps being provided with slit located contiguous to its hinged edge and the other having a tongue at its outer edge that engages in the slit, whereby the flaps may be detachably secured together.

5. In a pyramidal folding box, the combination with a bottom, of side walls hinged to the bottom and spaced from each other said walls tapering toward their outer ends, wings also hinged to the bottom between the side walls, said wings tapering toward their outer ends, flaps hinged to the side walls and adapted to be placed in overlapping relation over the wings when said side walls are set up, and detachably-interlocking means carried by the overlapping flaps for detachably securing them together.

6. In a pyramidal folding box, the combination with a rectangular bottom, of triangular side walls hinged to the opposite side edges of the bottom, wings hinged to the bottom between the side walls and tapering toward their outer ends, triangular flaps hinged to the side edges of the walls and being of the same size thereof, said flaps being adapted to be placed in overlapping relation over the wings when the walls are set up, one of the overlapping flaps having a tongue and the other a slit that receives the tongue whereby they are detachably secured together.

In testimony that I claim the foregoing as my own I have hereto affixed my signature in the presence of two witnesses.

JESS C. HOVER.
